ATTORNEY

UNITED STATES PATENT OFFICE.

JAMES S. WOOD, OF ALEDO, ILLINOIS.

HINGE FOR SLIDING AND ROLLING GATES.

SPECIFICATION forming part of Letters Patent No. 276,949, dated May 1, 1883.

Application filed October 4, 1882. (No model.)

To all whom it may concern:

Be it known that I, JAMES S. WOOD, a citizen of the United States, residing at Aledo, in the county of Mercer and State of Illinois, have invented certain new and useful Improvements in Hinges for Sliding and Rolling Gates; and I do hereby declare the following to be a full, clear, and exact description of the invention, such as will enable others skilled in the art to which it appertains to make and use the same.

This invention relates to certain new and useful improvements in hinges for sliding and rolling gates; and the invention consists in novel features of construction and combination and arrangement of parts, all as will be hereinafter fully described, and set forth in the claims hereto annexed.

Referring to the accompanying drawings, Figure 1 represents a side elevation of my improved hinge; Fig. 2, a vertical section through the same, showing its attachment to the gate-post; Figs. 3 and 4, detail views to be hereinafter referred to.

In the drawings, A represents the gate-post, to which my improved hinge is secured, and B an open metallic roller-frame, composed of the two half-sections b b', the right-angled portions b² b³ at the upper and lower ends 30 thereof overlapping each other to form close-fitting joints.

Within the frame B is journaled the roller C, having circular recessed sides c c', for the reception of the circular hubs c' c', (cast integral with the half-sections of the frame,) and a central opening, c², through said roller for the reception of the journal c³, cast integral with or otherwise secured to one of said hubs, so that when the two half-sections of the frame 40 B are rigidly secured together by the headed screw-bolts D and nuts d the roller C, upon which the gate is suspended, will also be secured in position, as shown in Figs. 1 and 3. Right-angled strengthening-ribs d' d' are formed on the outside of the half-sections of the roller-frame B.

The metallic roller-frame B is pivotally connected at its upper and lower ends to the gate-post A in the following manner: The upper or 50 top end of said frame is provided with a hole, e, (formed by semicircular recesses in the ends

of the right-angled portions b² b³ of the half-sections,) for the reception of the hooked end e' of a bent screw-bolt, E, which passes obliquely through the gate-post A, and secured by a nut and washer, e² and e³. 55

F represents a supporting bracket or brace, having a bifurcated end, f, adapted to embrace the corner and adjacent sides of the gate-post. This bracket or brace is provided at its other end with a right-angled plate, f', cast integral therewith, and having an upwardly-projecting headed lug, f², around the shank f³ of which fit the recessed ends of the right-angled portions b² b³ of the half-sections at the lower 65 end of the roller-frame, thus forming the hinge or journal upon which the lower end of roller-frame turns. The right-angled plate f' has also a downwardly-projecting lug, g, between which and the side of the bracket or brace fits 70 the square shank g' of the headed screw-bolt G, which also passes obliquely through the gate-post, and secured by the nut and washer g² and g³, as shown in Figs. 2 and 4.

The above-described manner of pivotally 75 connecting the roller-frame to the gate-post gives said frame a rigid and firm support, and prevents the gate from sagging when arranged in position to be supported upon the roller C.

All the parts are made of malleable or cast 80 iron, and can be easily and quickly connected together and to the gate-post.

Having thus fully described my invention, what I claim as new, and desire to secure by Letters Patent, is— 85

1. The metallic roller-frame B, composed of the half-sections b b', with right-angled portions b² b³, interior hubs, c' c', and journal c³, in combination with the roller C, having recessed sides and a central opening through it for the 90 reception of said hubs and journal, substantially as and for the purpose herein shown and described.

2. The combination, with the roller-frame B, formed in half-sections b b', of the brace or bracket F, having a bifurcated end, f, and a right-angled plate, f', provided with a headed lug, f², and lug, g, and the headed screw-bolt G, whereby the lower end of the roller-frame 95 is journaled and secured to the post, substantially as specified. 100

3. The combination, with the roller-frame B,

formed in half-sections *b b'*, of the brace or bracket *F*, having a bifurcated end, *f*, and right-angled plate *f'*, provided with a headed lug, *f²*, and lug *g*, and the screw-bolt *G*, and bent and hooked screw-bolt, whereby the upper and lower ends of the roller-frame are journaled and secured to the gate-post, substantially as specified.

In testimony whereof I affix my signature in presence of two witnesses.

JAMES SHERWIN WOOD.
